UNITED STATES PATENT OFFICE.

ARTHUR M. CARRIER, OF FRUITVALE, CALIFORNIA.

LOCK AND LATCH.

SPECIFICATION forming part of Letters Patent No. 759,591, dated May 10, 1904.

Application filed March 25, 1902. Renewed March 17, 1904. Serial No. 198,661. (No model.)

To all whom it may concern:

Be it known that I, ARTHUR M. CARRIER, a subject of the King of Great Britain, and a resident of Fruitvale, in the county of Alameda 5 and State of California, have invented new and useful Improvements in Mortise Locks and Latches, of which the following is a specification.

This invention relates to improvements 10 made in door-locks of that class or description which are set into the woodwork and are usually provided with a latch as well as a bolt; and the improvements comprise certain 15 novel construction of lock-casing, latch-controlling devices, and lock mechanism and the combination thereof in the production of a lock and latch, as hereinafter fully described and set forth.

In the following description, that explains at 20 length the nature of my said improvements and the manner in which the same are applied and carried out, the accompanying drawings are referred to by figures and letters.

Figure 1 of the drawings is a side view of a 25 door-lock embodying my invention, showing the lock set into the edge of a door, a portion of the woodwork immediately around the lock being represented in the figure with a portion broken away to partially expose the lock-casing. Fig. 2 is a reversed or back view of the escutcheon removed from the door. Fig. 3 is a side elevation of the lock before it is set, showing the sides of the latch-casing and bolt-casing broken away or removed to expose 30 the parts within. Fig. 4 is a rear view taken from the left side of Fig. 3, with the ends of the casing partly broken away. Fig. 5 is a cross-section at 5 5, Fig. 3, and Fig. 6 a similar section at 6 6, Fig. 3. Fig. 7 is a top view 35 of the latch, and Fig. 8 a top view of the lower one of the two slides in the latch-operating mechanism. Figs. 9, 10, and 11 are isometrical 40 projections of the parts of the lock-casing in detail detached from the front plate, and Fig. 12 a view of the front plate. Fig. 13 is a similar view of the bolt. Fig. 14 is a similar 45 projection of the partition-plate and the tumblers attached to it. Fig. 15 is a top view of the bolt, tumblers, and partition-plate separating the tumblers. Fig. 16 is an inverted

plan of the same parts, showing the key in position for operating the tumblers and the bolt. Fig. 17 is a perspective view of the key. Figs. 18 and 19 are plan and elevation of the bit of the key.

The two casings *a b* are united to the front plate *c* in line with the apertures *d e*, provided for the latch *f* and the bolt *g* to work through in that plate. The mechanism of the latch is inclosed in one casing, and the parts that operate the bolt are separately inclosed in the other casing. Each casing being of such form and size that it will fit a cylindrical hole in the woodwork is preferably formed of a tube having flattened sides, with the top and bottom arched in order to afford space internally to accommodate the mechanism and at the same time bring the sides as closely together as practicable. A tube of square or rectangular shape in cross-section could be used; but such shape would require a circular hole of large diameter to be made in the woodwork to admit the tubular casing, if the square tube were to have the same internal dimensions vertically as the cylindrical tube.

On one side of the tubular lock-casing is a removable plate 22, which in the lock-casing *b* is returned at the rear end 23 to cover that end of the tube, whereby the end of the tube is uncovered for drawing out the internal mechanism whenever the plate 22 is removed; but in the other casing, containing the latch, the end may be permanently closed and not made a part of the removable plate.

The operating mechanism of the latch *f* 85 comprises two bars *h h*, fitted to slide smoothly in the casing on opposite sides of a spur-pinion *n* and having spur-teeth on their adjacent faces meshing with the teeth of the pinion. That part when rotated in one direction or the other moves the slides in opposite directions, one forward and the other backward, the result of which is to draw back the latch *f* no matter in which direction the rotation of the pinion takes place. A lug 3 on the forward 90 end of each slide in line with and against or in close relation to a projection 2 on the tail end of the latch loosely connects the two slide-bars with the latch and allows one bar to become disengaged from the latch as the other 95 100

bar draws the latch back. The contrary movement of the latch to project it from the casing is effected by a coiled spring 4, having a bearing at the front end against the latch and 5 at the rear end against an abutment *g* in the casing. This part *g* is recessed at *i* to form a guide for the body of the latch, which is slotted or formed with two parallel legs to pass on opposite sides of the abutment. Bearings 10 are provided for the hubs or cylindrical ends of the pinion.

A spindle *e* extends through the hub of the pinion *m* and is provided with the usual knobs or handles on the ends for turning the pinion. 15 One of the knobs is indicated by dotted lines in Fig. 1. The other is removed by reason of the spindle *e* being shown in section.

Where a night-latch is desired on this lock, to prevent the latch from being operated from 20 the outside, I provide a locking device for that purpose that can be thrown on or off from the inside of the room by arranging a slide-plate 16 and a pivoted lever 17 in a recess in the back of the escutcheon-plate that contains the 25 holes *n* and *t* for the latch-spindle and the key, so that their parts being confined between the escutcheon-plate and the woodwork of the door have no communication with any of the apertures and cannot be reached from the out- 30 side. The lever 17 works on a pivot 19 and is attached at one end to the slide 16 and on its other end is provided with a finger-piece 20, projecting through a slot 21 in the es- 35 cutcheon-plate. The slide 16 has a rectangular slot 21, corresponding in width to the thickness of the latch-spindle, so as to grasp the same, and the lever 17 is attached to the slide by a stud 18, working in a slot in the lever.

The mechanism contained in the lower cas- 40 ing *b* is mounted on a removable plate *s*, that divides the chamber in the tube vertically into two longitudinal compartments of about the same dimensions in height and breadth. That plate is fitted to slide in and out through 45 the rear end of the casing when the side plate of the casing is taken off.

From its rear end to a point forward near the head the bolt *f* is divided into two legs or bars 6 6, having spaced notches 14 in the bot- 50 tom edges to engage the bit of the key and also recesses 8 9 in the top edges to receive the tumblers 12, and the two legs or members, while being a part of the head of the bolt, are separated from each other, with their tum- 55 blers, by the partition-plate, so that each leg and the tumbler that locks it works in a sepa- 60 rate compartment. The legs 6 at their rear ends are united by a cross-pin 7, passing through a slot 26 in the partition for the pur- 65 pose, chiefly, of preventing the legs from springing and keeping them in line. The slot being made equal in length to the throw of the bolt also serves as a stop to limit the throw in both directions. The tumblers *r* are piv- 70 otally attached by a pin 10 to the partition

and are fitted to play up and down between the partition and the legs of the bolt, each tumbler having a turned lip or flange 12 to lie over the top edge of the leg. This lip per- 75 forms the double office of locking the leg and of holding the tumbler in working position against the downward pull or strain of the spring 15. As thus constructed, it will be seen that the bolt is controlled by two sepa- 80 rate tumblers, which are situated in different compartments of the casing and which act in- 85 dependently of each other, so that the bolt cannot be thrown unless both tumblers on op- 90 posite sides of the partition are raised simul- 95 taneously by the key.

The bit of the key *w* is divided by a cleft 28, corresponding in width to the thickness of the partitions, and both parts are united by the stem or shank, from which part they project on opposite sides and in the same plane. Each 95 section has ribs or teeth 29 30 on the outer edge arranged equidistant from the shank, so as to move in the same circular path as the key is revolved in the lock. An intermediate tooth or rib 31 on the front face of the bit, 100 extending from the outer end to the cleft 28, forms a stop that arrests the further move- 105 ment of the key when the cleft is in line with the partition-plate at the time of inserting the key, and thereby insures the proper alinement 110 of the bit to set the two parts for action on opposite sides of the partition. In addition to this function of a stop the middle projec- 115 tion 31 forms an intermediate tooth that en- 120 gages the notch in the bottom edge of the leg 6 at the moment that the leading tooth on the outer edge of the bit working in the other compartment is disengaged from the leg in the revolution of the key, thus securing an even and continuous movement in either di- 125 rection of its throw.

As thus constructed it will be seen that a lock of this character with tubular casings can be set in a door in much less time than a mortise-lock with a single casing of rectangular shape for the reason that no mortising is required, and instead of boring six holes and then using the chisel it is only necessary in setting my lock to bore two holes at proper distance apart to admit the latch-casing and the lock-casing and then cut cross-apertures for the knob-spindle and the keyhole.

Having thus fully described my invention, what I claim as new therein, and desire to se- 130 cure by Letters Patent, is—

1. A combined lock and latch, comprising a casing having two separate tubular inclosures united rigidly to a common rim, an aperture in the rim in line with each tubular inclosure; a sleeve rotatably mounted in one tubular inclosure transversely thereof and having a rec- 135 tangular aperture for a latch-spindle; a slid- 140 able latch-piece, and mechanism operatively connecting the latch-piece with the rotatable sleeve, said latch-piece and operating mechan- 145

ism being wholly incased by said tubular inclosure; and a slidable bolt and lock mechanism wholly incased in the other tubular inclosure and comprising a stationary partition-plate dividing the tubular inclosure longitudinally; a slidable bolt slotted longitudinally and having a member fitted to slide in each compartment; a tumbler pivotally attached to the bolt member in each casing, said

- 5 5 tumblers being adapted to operate separately of each other; key-apertures in the sides of the tubular inclosure incasing the lock mechanism, and a key-aperture in the fixed partition-plate in line therewith; and a key having separate bits adapted to operate simultaneously 15 on the tumblers on opposite sides of the partition-plate.

2. In a mortise-lock, the combination of a casing comprising a rim having an aperture for 20 a bolt and a tubular inclosure rigidly fixed to the rim in line with the said aperture and adapted to wholly inclose the lock mechanism, a stationary partition-plate dividing the tubular inclosure longitudinally into two chambers, a slidable bolt having two parallel members fitted to slide in said chambers and separated from each other by the partition-plate, a tumbler pivotally attached to each bolt member, and catches in the bolt-chamber with 25 which the tumbler therein engages to lock the bolt, key-apertures in the sides of the tubular inclosure, and a keyhole in the partition-plate in line with said apertures.

3. In a mortise-lock, the combination of a 30 tubular casing, a partition-plate dividing said casing longitudinally into two chambers, and a bolt and tumblers operatively mounted on and separated from each other by the partition-plate, whereby the lock mechanism is 35 wholly removable by withdrawing the partition-plate, said plate having an aperture for a key and through which the tumblers in both

chambers are operated simultaneously from the same side of the lock.

4. In a mortise-lock, the combination of a 45 tubular casing, a partition-plate dividing said casing longitudinally and removable through the end of the casing and having a bolt and tumblers operatively mounted on the plate, whereby said parts are removable by withdrawing the plate from the casing.

5. In a mortise-lock, the combination of a 50 tubular casing, a removable partition-plate therein dividing the casing longitudinally into separate compartments, a bolt having a bifurcated rear portion comprising parallel legs, tumblers pivotally mounted on opposite sides of the partition-plate and a key-aperture in said plate.

6. In a mortise-lock, the combination of a 55 tubular casing having a bolt-slot in one end, an opening in the opposite end and a removable plate closing said opening; a partition-plate fitted to said casing to divide the same longitudinally into two separate chambers and 60 removable therefrom through the end of the casing; a slidable bolt having a bifurcated rear portion comprising a separate leg to each chamber, a tumbler in each chamber pivotally attached to the partition-plate and adapted to 70 separately control the leg in its chamber on the same side of the plate; a key-aperture in the partition-plate and a key fitted thereto having a divided bit the members whereof are adapted to engage the tumblers on opposite 75 sides of the partition-plate and simultaneously operate them.

In testimony whereof I have signed my name in the presence of two subscribing witnesses.

ARTHUR M. CARRIER.
